UNITED STATES PATENT OFFICE.

MELVILLE CLARK, OF CHICAGO, ILLINOIS.

COUPLER FOR PNEUMATIC-ORGANS.

SPECIFICATION forming part of Letters Patent No. 606,444, dated June 28, 1898.

Application filed July 30, 1897. Serial No. 646,475. (No model.)

To all whom it may concern:

Be it known that I, MELVILLE CLARK, a citizen of the United States, residing at Chicago, county of Cook, and State of Illinois, have invented certain new and useful Improvements in Couplers for Pneumatic-Organ, which are fully set forth in the following specification, reference being had to the accompanying drawings, forming a part thereof.

The purpose of this invention is to provide improved means for coupling octaves in pneumatically-operated reed-organs or other musical instruments whose sound-controlling devices are pneumatically actuated.

In the drawings, Figure 1 is a fore-and-aft section through a reed-organ having my improvement, one reed-valve and its operating mechanism, including the pneumatics and the manual-key connections, being shown. Fig. 2 is a detailed plan of the same structure in which the parts of four octaves of the primary pneumatics and coupling connections are shown. Fig. 3 is a detail elevation of a portion of the action corresponding to that shown in Fig. 1, illustrating a modified form of stop connections for operating the coupling-board. Fig. 4 is a detail elevation at the end of the coupling-board, showing a further modification of the coupling mechanism. Fig. 5 is a detail plan of the construction illustrated in Fig. 4.

The general structure of the organ herein illustrated is that which I have used heretofore and which is shown in several patents heretofore granted to me.

A is the wind-chest; B, a reed-block; C, the reed-controlling valve; D, the motor-pneumatic or reed-valve-actuating pneumatic; E, the primary pneumatic, whose function is, by means of the valves F^a and F^b, mounted on a common stem carried by said pneumatic, to control the communication of the motor-pneumatic with the wind-chest and with the outer air, and thereby cause the action of said motor-pneumatic to actuate the reed-valve.

F is a duct leading from the primary pneumatic to a post j in board J, which is controlled by valve g on the lever G, which is provided with a spring G^a, tending to hold the valve g seated. The lever G is actuated by the pitman H^a on a manual-key H. It will

be understood that the depression of the manual-key lifting the valve g and venting the primary pneumatic will cause the latter to be inflated and to close the communication of the motor-pneumatic with the outer air and open communication with the wind-chest, thus causing said motor-pneumatic to be collapsed and to actuate the reed-valve C by means of the connecting-tape c. The duct f, of which the tube F is a continuation and through which the primary pneumatic is vented, has a branch F^a, which may lead to a tracker-range, (not shown,) where it may be controlled by a perforated music-sheet (not shown) for the purpose of venting the primary pneumatic and operating the instrument automatically. These self-playing appurtenances are not illustrated, because their action, so far as the present invention is concerned, is precisely equivalent to that caused by the depression of the manual-key, and it may be understood that the coupler devices which constitute the invention and which will now be described perform their function in precisely similar manner whether the instrument is operated by the manual or by the self-playing appurtenances.

For the purpose of coupling octaves I mount upon the upper side of the board X, upon the lower side of which the motor-pneumatics D are mounted, the coupler-board L, in which are formed ducts l l, &c., which open at the upper surface of the board and at the rear edge thereof, the openings at the upper surface being closed by valves M M M, &c., which are located in position above the motor-pneumatics, respectively, which have projecting fingers M^a M^a, &c., which overhang the fingers D^a D^a, which project up rigidly from the lower or fluctuating walls of the pneumatics. Tubes N N, &c., connect the rear ends of the ducts l l with the octave distant primary pneumatics, respectively. The tubes N N, &c., are flexible and should be made with a slight excess of length to allow for some movement of the board L. The board L may be mounted either pivotally at its rear edge and adapted to tilt up at its forward edge to carry the valve-fingers M^a out of range of the upward thrust of the motor-pneumatic fingers D^a, as shown in Figs. 1 and 2, or it may be arranged to slide longi-

tudinally on the board X to carry the valve-fingers laterally out of range of the pneumatic fingers respectively. Suitable mechanical connections from a stop-rod P to the board L will effect the shifting of the board from one position to the other. In case the board is pivoted the connection may be that shown in Fig. 1, which consists of a bell-crank lever Q, having one arm connected with the stop-rod and the other arm connected by link Q^a with the board L. If the coupling-board is arranged to slide instead of tilt, I provide for the purpose a vertical rock-shaft S, which may have a lever-arm S' at the lower end connected to the stop-rod M and the lever-arm S^a at the upper end arranged to engage the board L. With this structure it will be understood that when any motor-pneumatic is operated and causes the corresponding sound-producing device to speak the action of such motor-pneumatic opening the valve M vents the octave distant primary pneumatic, whereby the motor-pneumatic corresponding to the latter is also operated and causes its sound-producing device to speak, thus coupling the octaves.

For the purpose of coupling the range of the instrument is preferably divided into an upper and a lower half, so that above the division-point the coupling may be made upward and below that point it may be made downward. The coupling-board is preferably divided at the corresponding point and the two sections operated by separate stops, the connections being precisely the same in the two cases; but the tubes M on the right-hand or upper board will diverge upwardly from the divisional plane to the octave distant primary pneumatics, and the tubes on the lower or left-hand board will diverge downwardly to the octave distant primary pneumatics.

I claim—

1. In a pneumatically-operated musical instrument, in combination with the motor-pneumatics and the primary pneumatics which operate them, vent-valves for the primary pneumatics respectively, and mechanical

connections by which the motor-pneumatics may actuate the vent-valves of the octave distant primary pneumatics respectively.

2. In a pneumatically-operated musical instrument, in combination with the motor-pneumatics and primary pneumatics which operate them; vent-valves for the primary pneumatics respectively; movable mechanical connections by which the motor-pneumatics may actuate the vent-valves of the octave distant primary pneumatics, and means for moving the same into and out of movement-communicating position.

3. In a pneumatically-operated musical instrument, in combination with the motor-pneumatics and the primary pneumatics which operate them respectively; ducts leading from the primary pneumatics and valves which control such ducts located proximate to the octave distant motor-pneumatics respectively; and mechanical connections by which the motor-pneumatics act upon such proximate primary pneumatic valves to cause their respective sound-producing devices to speak.

4. In a pneumatically-operated musical instrument, in combination with the motor-pneumatics and the primary pneumatics which operate them; a coupler-board and ducts leading from the primary pneumatics respectively to such board; valves on the board which control the ducts respectively located proximate to the motor-pneumatics which are an octave distant from the primary pneumatics from which the ducts respectively lead; abutments extending from the motor-pneumatics and adapted to encounter their proximate valves respectively, the board being movable to carry such valves into and out of the range of the motor-pneumatic abutments respectively.

Chicago, July 23, 1897.

MELVILLE CLARK.
